(57)

CLAIM

The ornamental design for a wrist brace as shown and described.

DESCRIPTION

FIG. 1 is a perspective view of a wrist brace;

FIG. 2 is a front view of the wrist brace;

FIG. 3 is a rear view of the wrist brace;

FIG. 4 is a side view of the wrist brace;

FIG. 5 is the opposite side view of the wrist brace shown in FIG. 4;

FIG. 6 is a top plan view of the wrist brace; and,

FIG. 7 is a bottom plan view of the wrist brace.

The dashed broken lines on the drawing views of FIGS. 1-7 depict portions of the wrist brace that form no part of the claimed design.

1 Claim, 6 Drawing Sheets
